CLOTHING APPLIQUÉ

Samuel Sandhaus, New York, N. Y.

Application July 8, 1953, Serial No. 25,847

Term of patent 7 years

(Cl. D3—9)

FIG. 2.

To all whom it may concern:

Be it known that I, Samuel Sandhaus, a citizen of the United States, resident of the city, county, and State of New York, have invented a new, original, and ornamental Design for Clothing Appliqué, of which the following is a specification, reference being had to the accompanying drawing, forming part thereof.

In the drawing,

Fig. 1 is a plan view of a clothing appliqué showing my new design; and

Fig. 2 is an edge view of the new design shown in Fig. 1.

The essential feature of the design is illustrated in the portion shown in full lines in the drawing, the backing or support of the design being conventional in appearance and shown in dot-dash lines.

I claim:

The ornamental design for a clothing appliqué, substantially as shown and described.
